CLAIM

The ornamental design for a beverage container, as shown
and described.

DESCRIPTION

FIG. 1 is a top perspective view of a beverage container
showing my new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.

The evenly-dashed broken lines in the drawings illustrate the
portions of the beverage container that form no part of the
claim. The dot-dash broken lines in the drawings define the
bounds of the claim and form no part thereof.
